 In France May 29, 1934

13 Claims. (Cl. 205—18)

Electric resistances, conductors or cables are now in use wherein the insulating material consists of a mineral powder enclosed by any suitable external covering.

Such cables, which possess the great advantage of being incombustible, are usually manufactured in one of two ways. The more simple manner consists in disposing in a metallic tube, the cylinder or cylinders constituting the conductors, then filling the hollow space between the tube and the conductors with the mineral powder, and thereafter submitting this assemblage to a lengthening treatment say by rolling or drawing. Another manner giving rise to successful results consists in forming the mineral powder in situ; for example magnesium strips are wound round the conductors or wires and are disposed inside the outer sheath, tube or the like; then a current of steam is caused to flow inside said sheath; the magnesium is thus transformed into magnesia, which expands and entirely fills the hollow space remaining between the conductors and the inner wall of the sheath. This assembly may then be submitted to the mechanical lengthening treatment as above.

The first of the above disclosed procedures presents the drawback that it is very difficult to prevent the conductors from being displaced slightly with reference to the sheath during the different operations, so that the cable consequently is not exactly centered.

The present invention is directed to an improved method of manufacture of cables of this kind, and consists in disposing the insulating material around the conductors after having first imparted to this material the form of elements of compressed powder the said elements retaining the conductors in their respective places. When it is desired to manufacture only a relatively short rough piece of cable which must be subsequently lengthened it is possible to use elements shaped as cylinders and provided with holes through which are engaged the metallic bars which are intended to serve as the conductors; likewise, if it is desired to prepare long rough pieces or even true cables, each of the above disclosed elements are divided into several parts by longitudinal sections, say plane or helical, and said parts are juxtaposed on the conductors and are held in their places by a suitable sheath such as a metallic tube, a braiding, a covering or the like.

The following disclosure with reference to the annexed drawing indicates by way of example different forms of execution of the invention.

Figure 1 is a perspective view of an element used

in a rough piece intended to be lengthened for producing a cable having three conductors.

Fig. 2 is a cross-section of a rough piece for a cable having a single conductor.

Figs. 3 and 4 are cross-sectional views showing 5 elements capable of being interlocked with each other.

Fig. 5 shows part of an element capable of being used either for a rough piece intended to be lengthened or for true cable of considerable 10 length.

Fig. 6 shows how the parts of elements illustrated in Fig. 5 may be used for manufacturing a continuous cable.

Fig. 7 is a perspective view of an element having 15 a helical section.

Fig. 8 shows an element of modified shape.

In order to prepare a short rough piece which is to be further submitted to a lengthening process as by drawing, rolling or any other mechanical method, it is possible to use cylindrical blocks 20 formed of compressed powder, provided with apertures through which are engaged the metallic bars which are to serve as the conductors.

Fig. 1 shows such a block designed to be used 25 in a cable having three conductors; Fig. 2 shows a rough piece prepared for manufacture by lengthening an insulated conductor covered with a tubular sheath.

On a conductive stem 1 of copper, are disposed 30 cylindrical elements 2, made of compressed powder, similar to those of Fig. 1 with the exception that they are each provided with a single aperture instead of with three. These blocks or elements are formed from mineral powder, which is 35 compressed in moulds by any suitable machine, the powder at that time being either dry or wetted in order to produce a dough.

The assembly is surrounded by a sheath 3, say a lead tube, whereupon the final assembly is 40 lengthened by a suitable mechanical process such as rolling, drawing, or the like; during all those operations the elements 2 keep the conductor 1 centered in the axis of sheath 3, and as a consequence of the lengthening operation, these elements are crushed and the mineral material returns to its original state; i. e. reduced to powder. 45

In order to increase the coherency of the elements, they may be soaked before use in a suitable solution such as boric acid. It is also possible to provide the apertured blocks on their inner or outer ends or both with very thin sheaths of either metal or paper the thickness of which is negligible with reference to the other dimensions of the element, the central bore 50

55

thereof remaining of course uncovered. In assembling the cable, it is advantageous to dispose the sheath inside the moulds before the powder is compressed therein to form the elements, or if desired, the sheath may also be applied around a previously prepared element. Finally the sheath may also consist of a suitable coating which becomes solid upon drying.

In order to prevent the elements from being displaced sidewise with respect to each other, it is possible to impart to them such a shape that they interlock. Fig. 3 shows several elements interlocked with each other by virtue of their frusto-conical joints 7. These elements are shown as encased in inner and outer sheaths 8 and 9 of suitable material, say in paper.

Fig. 4 shows in cross-section a single element provided at one end with a spherical central recess and at the other end with a similarly shaped projection, so that the projection of one element may penetrate in the recess of the following one.

The elements are always provided with inner and outer sheaths 8 and 9. It is moreover obvious that many other shapes might be provided for and those shown in the drawing are simply by way of example.

The procedure of engaging the apertured elements on the conductive bars obviously can be applied only for short bars; it is thus possible to prepare in this manner only rather short rough pieces which are to be changed by lengthening into resistances or cable sections. However it is impossible to use this method when the elements are to be disposed around conductors which afterwards are to be submitted to only a slight lengthening treatment or are even not to be lengthened at all.

In this last case the elements are divided into several parts by longitudinal sections. For instance it is possible to divide elements such as those shown in Fig. 3 or 4 by one or more planes either passing through the axis or avoiding said axis in order to lengthen the leak lines capable of passing through the joints. By leak lines we mean the path followed by the current in passing from the conductor to the outer sheathing between the insulating elements. Fig. 5 is a perspective view of one half of an element 13 similar to that represented in Fig. 4.

Fig. 6 shows by way of example how a single wire cable provided with an external braiding may be manufactured in a continuous manner by means of parts of elements such as those represented in Fig. 5.

Wire 1 is driven in a continuous manner in the direction of the arrow; during its progression it penetrates elements 11, 12 similar to those of Fig. 5 so that these latter are disposed around it. The figure shows an element 13 just ready to be positioned in place, the assembly is wrapped with a braiding 14, say of textile material, by means of any convenient known machine. The elements such as 13 are disposed on the wire just at the point where the braiding is woven into position. It is easy to see in the figure that the elements are kept in place at the same time by being interlocked by means of their projections and recesses and by being enclosed in the braiding. Of course it would be better to stagger the planes forming the joints of the consecutive elements with reference to each other.

In order to prevent the elements from sliding on each other, the sections, instead of being planes, may be given the shape of helical sur-

faces, and more particularly that of square threaded screws, or better of helical surfaces the generatrix of which remains parallel to those of a cone but do not meet the axis, in order to lengthen the leak lines passing through the joints. Fig. 7 represents an element similar to that illustrated in Fig. 4 but divided into two parts in the manner suggested above.

The elements could of course each be divided into any desired number of parts by such helical sections.

More particularly a shape may be imparted to the parts of elements which is limited on the one hand by cylindrical surfaces and on the other hand by square threaded screw surfaces as illustrated in Figure 8.

What we claim is:

1. A proceeding for manufacturing electric insulated conductors with an external sheath and a mineral insulating material consisting in preparing elements with a compressed powder of the insulating material, said elements being disposed between the conductors and sheath and the whole being then submitted to a mechanical lengthening treatment.

2. A proceeding as claimed in claim 1 wherein the compressed elements are soaked in a solution increasing their cohesion.

3. A proceeding as claimed in claim 1 wherein the elements are provided with at least one aperture so disposed as to be capable of being engaged on bars adapted to become conductors after lengthening, the external cylindrical surfaces of the element being covered with a thin layer of suitable material.

4. A proceeding as claimed in claim 1 wherein the elements are provided at least with one aperture disposed to be able to be engaged on bars intended to become conductors after lengthening, the surface of the apertures of the element being covered with a thin layer of suitable material.

5. A proceeding as claimed in claim 1 wherein the elements are provided at least with one aperture disposed to be able to be engaged on bars intended to become conductors after lengthening, the external surface of the element and the inner surface of the apertures of the element being covered with a thin layer of suitable material.

6. A proceeding as claimed in claim 1 wherein the elements are provided at one end with a recess and at the other end with a similarly shaped projection.

7. A proceeding as claimed in claim 1 wherein the elements are provided at least with one aperture disposed to be able to be engaged on bars intended to become conductors after lengthening, the external cylindrical surface of the element being covered with a thin layer of suitable material, the elements being provided at one end with a recess and at the other end with a similarly shaped projection.

8. A proceeding as claimed in claim 1 wherein the elements are provided at least with one aperture disposed to be able to be engaged on bars intended to become conductors after lengthening, the surface of the apertures of the element being covered with a thin layer of suitable material, the elements being provided at one end with a recess and at the other end with a similarly shaped projection.

9. A proceeding as claimed in claim 1 wherein the elements are provided at least with one

aperture disposed to be able to be engaged on
bars intended to become conductors after length-
ening the external surface of the element and
the inner surface of the apertures of the ele-
ment being covered with a thin layer of suitable
material, the elements being provided at one
end with recess and at the other end with a
similarly shaped projection.

5. 10. A proceeding as claimed in claim 1 where-
in each element is divided in several parts dis-
posed to be applied against one another round
the conductor.

10. 15. A proceeding as claimed in claim 1 where-
in each element is divided in several parts by
planes.

12. A proceeding as claimed in claim 1 where-

in each element is divided in several parts so
disposed as to be capable of assembly together
about the conductor, the sections being shaped
as helical surfaces.

13. A proceeding as claimed in claim 1 where-
in each element is divided in several parts so
disposed as to be capable of assembly together
about the conductor, the sections being shaped
as helical surfaces, each element being provided
at one end with a recess and at the other end 10
with a similarly shaped projection.
